CLAIM

The ornamental design for a light emitting diode, as shown and described.

DESCRIPTION

FIG. 1 is a top perspective view of a light emitting diode showing the new design;

FIG. 2 is a bottom perspective view thereof;

FIG. 3 is a top plan view thereof;

FIG. 4 is a bottom view thereof;

FIG. 5 is a front view thereof;

FIG. 6 is a right side view thereof;

FIG. 7 is a cross-sectional view taken along line 7—7 in FIG. 3; and,

FIG. 8 is a cross-sectional view taken along line 8—8 in FIG. 3.

The broken lines represent unclaimed subject matter.
